United States Patent Office

Des. 222,007

Patented Sept. 21, 1971

222,007

PILLOW DISPLAY STAND

James T. Peterson, Prospect Heights, Ill., assignor to
Mohasco Industries, Inc., Amsterdam, N.Y.

Filed Dec. 15, 1969, Ser. No. 20,490

Term of patent 14 years

Int. Cl. D6—06

U.S. Cl. D80—9

The figure shown is a perspective view of a pillow display stand illustrating my new design. The sides not shown are substantially identical to the sides shown.

I claim:

The ornamental design for a pillow display stand, substantially as shown and described.
